(57) **CLAIM**

The ornamental design for a paper cartridge for a printer, as shown and described.

DESCRIPTION

FIG. 1 is a top perspective view of a paper cartridge for a printer with a cover in the closed position;

FIG. 2 is a bottom perspective view thereof;

FIG. 3 is a top view thereof;

FIG. 4 is a front view thereof;

FIG. 5 is a right-side view thereof;

FIG. 6 is a left-side view thereof;

FIG. 7 is a rear view thereof;

FIG. 8 is a bottom view thereof;

FIG. 9 is a reduced top view thereof in an unfolded and open position;

FIG. 10 is a reduced bottom view thereof in an unfolded and open position;

FIG. 11 is a top perspective view of the paper cartridge for a printer with the cover in an open position;

FIG. 12 is a bottom perspective view thereof;

FIG. 13 is a top view thereof;

FIG. 14 is a front view thereof;

FIG. 15 is a right-side view thereof;

FIG. 16 is a left-side view thereof;

FIG. 17 is a rear view thereof; and,

FIG. 18 is a bottom view thereof.

The broken lines depict environmental subject matter only and form no part of the claimed design.
